Patented July 14, 1914.

UNITED STATES PATENT OFFICE.

WINTHROP KEITH HOWE, OF ROCHESTER, NEW YORK, ASSIGNOR TO GENERAL RAILWAY SIGNAL COMPANY, OF GATES, NEW YORK, A CORPORATION OF NEW YORK.

DIVIDED SEMI-AUTOMATIC SIGNAL-LEVER.

1,103,206.

Specification of Letters Patent. Patented July 14, 1914.

Application filed January 19, 1912. Serial No. 672,070.

To all whom it may concern:

Be it known that I, WINTHROP KEITH Howe, a citizen of the United States, and resident of the city of Rochester, in the 5 county of Monroe and State of New York, have invented a new and useful Divided Semi-Automatic Signal-Lever, of which the following is a specification.

This invention relates to electric interlocking systems and particularly to an arrangement and combination of devices for controlling a semi-automatic dynamic return indication signal.

The primary object of this invention is to 15 so construct a lever and so arrange the connections between the lever and semi-automatic signal, that a return indication may be received at the lever, by means of the ordinary and well known form of indication 20 mechanism, caused by a current of electricity generated by the signal in returning to the danger position when such signal returns to the danger position by reason of the entrance of a train upon the track section controlled by the signal.

It is impossible, practically, to control the ordinary type of automatic signal in the manner which is commonly known as semi-automatically. This impossibility is due to 30 the fact that the signal in returning to danger position on account of the entrance of a train upon the track section controlled by the signal does not generate an indication current for the reason that the lever in the 35 interlocking machine controlling the signal is at that time in the wrong position to close the indication circuit. Heretofore electrically operated signals, not suitable for use as an automatic signal have been 40 controlled semi-automatically by means of the ordinary and well known type of lever as employed in the all electric interlocking system and heretofore electrically operated signals suitable for use as automatic signals 45 have been controlled in an all electric interlocking system by means of a lever so constructed and arranged that a change in the ordinary and well known form of indication mechanism as used in electric interlocking systems, was necessary. It is extremely desirable for many reasons, perfectly obvious, to have one type of signal

mechanism suitable for use as a manually controlled signal, as a semi-automatically controlled signal and as an automatically controlled signal and it is also desirable to have one uniform indication mechanism for use with both a manually controlled signal and with a semi-automatically controlled signal. Applicant's invention supplies the 55 above mentioned want, for by it a signal which is suitable for all the ordinary types of control may be used in connection with a lever which is governed by the ordinary and well known type of indication mechanism, consequently on a railroad which employs one type of signal both as an automatic signal and as a manually controlled signal, the same signal may be employed as a semi-automatic signal by merely changing 60 the less complicated parts of the interlocking machine used for governing the manually controlled signal, to-wit: the lever or slide.

In describing the invention in detail, reference will be had to the accompanying drawing which shows a preferred form of applicant's invention, in which,—

Figure 1 is a view in elevation, of a lever, together with associated parts. Fig. 2 is a 80 diagrammatic representation of the lever of applicant's invention together with the associated signaling circuits. Fig. 3 is a cross sectional view of the lever and its guide, as shown in Fig. 1, on the line A—B, 85 looking in the direction of the arrow a. Fig. 4 is a view in cross section of the lever as shown in Fig. 1, on the line C—D, looking in the direction of the arrow b.

Similar characters of reference refer to 90 like parts throughout the several views.

1, designates a lever or slide, formed in two parts, 2 and 3 abutting each other at the line 4. The part 2 contains the cam slot 5, which, by proper connection, is adapted to actuate a tappet controlling mechanical locking, and thus control the other levers in the same machine with it in the manner well understood by those skilled in the art. The part 2 has the upstanding projection 6, which supports a pivot pin 7, upon which is mounted the latch 8 bearing the armature 9, which armature is adapted to engage with the projection 10, fastened to the part 95 100

3. The part 2 also carries the electromagnet 11. Both portions of the lever are supported and guided by the lever guide 12, which bears the indication mechanism consisting of a latch 13 supported by a pin 14, attached to the lever guide 12; a dog 15 supported by a pin 16, fastened to the lever guide; a cam 17 supported by the pin 18, fastened to the lever guide 12; and the indication magnet 19 which has an armature 20, to which is fastened a rod 21. The latch 13 is spring held in the position shown by the spring 22, fastened at 23 to the lever guide 12. The cam 17 is adapted to be moved into two positions and be held therein resiliently by means of spring 24. The portion 3 of the lever 1 has the shoulders 25, 26, 27, 28, 29, 30 and 31.

When all of the parts are in the normal position, they are as shown in Fig. 1, but if both parts of the lever are moved to the reverse indication position, the shoulder 26 will engage with the left hand end of the latch 13, thereby raising the right hand end of the latch so that it will lie in the path of the shoulder 30, and the shoulder 30 when passing cam 17 will engage with the tooth thereof, rotate the cam and cause the left hand end to engage with the upper end of dog 15 forcing it under the right hand end of latch 13 if it has not already moved to such position by virtue of spring 22 so as to hold the latch in the moved position, so that shoulder 30, after engaging with the right hand end of the latch 13, may not push latch 13 down out of the way. The parts being in the position as described, an energization of indication magnet 19 will cause armature 20 to be raised, carrying with it rod 21, the upper end of which will strike the lower arm of dog 15 and force it from under the right hand end of latch 13, thereby allowing the shoulder 30 to force the latch 13 down out of the way and allow the lever to be moved to the full reverse position. The shoulders upon the member 3, the latch 13, the dog 15, the pin 18, the indication magnet 19, the armature 20, and rod 21 are all fully shown, described and claimed in Patent #752,127, granted to John D. Taylor, February 16, 1904.

The lever guide 12 at its extreme right ends, bears the pin 32, having the lever 33 mounted thereon, and also has the pin 34 adapted to contact with one arm of the lever 33 when the lever is in the extreme position as shown in Fig. 1. The upper arm of the lever extends into a recess 35 of the part 3 of the lever and bears against a pin 36 attached to the part 3. The lower arm of the lever bears the weight 37.

When both parts of the lever have been moved to the full reversed position, the weight 37 exerts a force upon the part 3 of

the lever tending to return it to the normal position as shown, but as well understood by those skilled in the art of railway signaling, and as fully explained in the patent above referred to, if a lever of the type described should be moved from the reverse position toward the normal position, it would be stopped at the normal indication position by the shoulder 29 contacting with the shoulder 38 of the latch 13 and the lever would remain in such position until the magnet 19 was energized and the armature and rod 21 lifted. In the type of lever here shown and described, such action would also take place and after the indication had been received the part 3 of the lever would be returned to the position as shown in Fig. 1, by virtue of the action of the weight 37 upon the pin 36 through the intermediary of the lever 33.

In Fig. 3, a cross section upon the line A—B of Fig. 1, is shown, in which the lever guide 12 is shown, and also the other half of the lever guide 39, not shown in Fig. 1.

In Fig. 4, a cross section of the lever and its guide as shown in Fig. 1, is shown.

Referring to Fig. 2, 40 and 41 designate two rails of a railway track; 42 and 43 insulations at either end separating the rails electrically from the remaining portions of the track; 44, a source of current connected across the rails at one end; 45 a relay connected across the rails at the other end; 46 designates generally a semaphore mechanism; 47 a source of current; 48 a rod connected to the part 3 of the lever bar and conducting block 49, which is adapted to connect springs 50 and 51 in the position shown and when the lever is in the reverse indication or full reverse position, to connect springs 52 and 53.

With all of the parts in the position as shown in Fig. 2, current flows from the positive side of battery 47 by means of wires 54 and 55, through relay coil 11, to wire 56, armature 57, and wires 58, 59, and 60, to the negative terminal of the battery. Current flowing in the above traced path energizes electromagnet 11 and causes armature 9 attached to latch 8 to be firmly held in position so that when the part 2 of the lever 1 is moved by grasping and pulling upon the handle 61, both parts of the lever will move together. This above circuit will be closed just so long as no train stands upon the rails 40 and 41 for reasons well known to those skilled in the art. If current does not flow in the above path, a pull upon the handle 61 will separate the portion 2 from the portion 3, instead of causing them to move in unison. If with all the parts as shown in Fig. 2, the handle 61 is pulled in the direction of the arrow d, the conducting block 49 will be moved into contact with

springs 52 and 53, and current will then flow in the following path; positive terminal of the battery 47, wires 54 and 62, spring 53, block 49, spring 52, wires 63 and 64 to the 5 fixed contact strip 65 and then by means of the movable contact strip 66, which moves in unison with the semaphore arm 67, to fixed contact 68 and through wire 69, field 70, wire 71, field 72, wire 73, brush 74, armature 75, brush 76, and wires 77, 59, and 60 10 to the negative terminal of the battery. Current flowing in the above traced path will cause the armature 75 to revolve and move the semaphore arm 67 to an operated 15 aspect, at which time the movable contact 78, moving in unison with the semaphore will make contact between fixed contact strip 79 and fixed contact strip 80, and at the same time movable contact strip 66 will 20 move out of contact with fixed contact 68, so that the current will then flow from wire 63 to wire 81, fixed contact 79, movable contact 78, fixed contact 80, through wire 82, field 83, wire 84, field 85, field 70, wire 71, field 72, 25 wire 73, brush 74, armature 75, brush 76 and wires 77, 59 and 60 to the negative terminal of the battery. In a manner well understood by those skilled in the art, the semaphore 67 will be held in the full clear 30 position by current flowing in the last described path, and the lever 1, will be in the full reverse position as both parts of the lever are held together by means of latch 8 and the weight 37 cannot move the lever 35 when released by the hand from its full reversed position as when both parts of the lever are connected together by latch 8, the part 2 of the lever is held in the reverse position by the latch 86 bearing against any 40 suitable stationary member, as 90 therefore the two parts being held firmly together and one part being held from movement, no movement of the lever as a whole can take place.

45 If a train should enter upon the rails 40 and 41 while the semaphore was in an operated aspect and the lever was in the reverse position, as described, the relay 45 would be deenergized and armature 57 would drop, 50 thereby breaking the circuit through electromagnet 11, thus allowing latch 8 to slip over projection 10, if force is exerted upon the member 3 to move it in the direction of the arrow *c*, Fig. 1, and such force would be 55 exerted by the weight 37 acting through the lever 33 and pin 36. The part 3, in moving in the direction of the arrow *c*, by reason of weight 37, would, in the well known manner be stopped at the normal indication position, and would also cause the block 49 to 60 contact springs 50 and 51. The movement of block 49 from between springs 52 and 53 would break the circuit, holding the signal in the operated position, consequently,

the signal, by reason of its bias, would move 65 toward the biased position and in so doing, in a manner well understood, would generate a current which, by reason of the fact that springs 50 and 51 are connected together, would flow in the following path: 70 armature 75, brush 76, wires 77, 59 and 87, indication magnet 19, wire 88, brush 51, block 59, brush 50, wire 89, wire 63, wire 64, fixed contact 65, movable contact 66, which, by the movement of the semaphore 75 to the biased position has moved to the position shown, fixed contact 68, wire 69, field 70, wire 71, field 72, wire 73 and brush 74 to the other terminal of the armature. The current generated by the armature 75, by 80 flowing in the path traced above, would energize indication magnet 19, and release latch 13 from in contact with shoulder 29, whereupon the weight 37, acting through lever 33 and pin 36, would return the part 85 3 to the full normal position. At any time thereafter, the operator may return the part 2 of the lever 1 into contact with the part 3 ready for another operation, but until such return no conflicting signals can be 90 cleared, as the mechanical locking would interfere.

It must be readily seen that if a train is upon the rails 40 and 41, the armature 57 would be dropped, consequently the electromagnet 11 would be deenergized and a pull upon lever 1 would only result in moving the part 2, although the part 2 could be moved from the full normal position as shown to the full reverse position, no undesired results could arise for the mechanical locking would be thereby actuated and, consequently, signals governing movements opposed to semaphore 67, could not be cleared. It is to be understood, of course, that if no 105 train is present upon the rails 40 and 41 the lever 1 could be operated in the same manner as the lever described in the patent to Taylor above mentioned.

Having thus explained the principle of 110 my invention and described one specific embodiment thereof, what I claim as new and desire to secure by Letters Patent, is:

1. In an interlocking system, a lever adapted for movement between a normal and 115 a reverse position and formed in two parts, mechanical locking, coöperating means attached to each part including an electromagnet for holding the parts together, one of said parts having means for operating 120 said mechanical locking indication mechanism associated with the other part and means constantly tending to move the said other part to normal position.

2. In an electric interlocking system, a 125 source of current, a signal having an operated and a biased aspect, means including a manually operated device to complete a

4

circuit from said source through said signal to cause said signal to assume an operated aspect, means connected with said manually operated device to break said circuit, a track 6 circuit section including a translating device for causing said means to automatically act, and means connected with the manu-

ally controlled device to automatically indicate a return of the signal to biased position on account of the breaking of the circuit.

WINTHROP KEITH HOWE.
